DESIGN FOR A TOY

Lloyd E. Pollard, Los Angeles, Calif.

Application January 29, 1944, Serial No. 112,371

Term of patent 7 years

(Cl. D34—15)

To all whom it may concern:

Be it known that I, Lloyd E. Pollard, a citizen of the United States, residing at Los Angeles, in the county of Los Angeles and State of California, have invented a new, original, and ornamental Design for a Toy, of which the following is a specification, reference being had to the accompanying drawing, forming part thereof.

Fig. 1 is a side view of the toy showing my new design; the opposite side being the same; and

Fig. 2 is a top view thereof; and

Fig. 3 is a front view thereof.

I claim:

The ornamental design for a toy, as shown

LLOYD E. POLLARD.
